(57) **CLAIM**

We claim the ornamental design for a selector for a control panel of exercise equipment, as shown and described.

DESCRIPTION

FIG. 1 is a front perspective view of a selector for a control panel of exercise equipment;

FIG. 2 is an enlarged front perspective view of the selector of FIG. 1;

FIG. 3 is a front view of the selector of FIG. 1;

FIG. 4 is a first side view of the selector of FIG. 1;

FIG. 5 is a second side view of the selector of FIG. 1;

FIG. 6 is a top view of the selector of FIG. 1; and,

FIG. 7 is a bottom view of the selector of FIG. 1.

The ornamental design that is claimed is shown in solid lines in the drawings. The broken (dashed) lines shown in the drawings are included for the purpose of illustrating environmental elements only and form no part of the claimed design.
